UNITED STATES PATENT OFFICE.

MARY S. C. HARTMANN, OF OAKLAND, CALIFORNIA.

DESIGN FOR A GAS-PLATE.

45,339.

Specification for Design.

Patented Mar. 3, 1914.

Application filed December 15, 1913. Serial No. 806,928. Term of patent 14 years.

To all whom it may concern:

Be it known that I, MARY S. C. HARTMANN, a citizen of the United States, residing at Oakland, county of Alameda, State of California, have invented a new, original, and ornamental Design for Gas-Plates, of which the following is a specification, reference being had to the accompanying drawings, forming part thereof.

Figure 1 is a plan view of the gas plate.

Fig. 2 is a vertical cross section on line X—X, Fig. 1.

I claim:

The ornamental design for a gas plate, as shown.

MARY S. C. HARTMANN.

Witnesses:

SARAH GROTEFEND,
DAVID E. ROSLING.
